UNITED STATES PATENT OFFICE.

ALTON R. WEAVER, OF ALAMEDA, CALIFORNIA.

AUTOMATIC GAS-COCK.

1,134,932.

Specification of Letters Patent.

Patented Apr. 6, 1915.

Application filed March 30, 1914. Serial No. 828,397.

To all whom it may concern:

Be it known that I, ALTON R. WEAVER, a citizen of the United States, residing in the city and county of Alameda and State of California, have invented a new and useful Improvement in Automatic Gas-Cocks, of which the following is a specification.

My invention relates to automatic gas cocks wherein a valve is normally closed and 10 may be held in an open position by an expansion rod in the vicinity of a gas jet heated by the combustion of the burning gas, and the objects of my invention are first, to provide means for retaining a gas cock in 15 an open position while the gas jet is burning; and second, to provide improved means for releasing the cock and allowing the same to close when the flame has been extinguished.

20 I accomplish the above by means of the device disclosed in the drawings forming a part of the present specification wherein like characters of reference are used to designate similar parts throughout the said specification and drawings, and in which—

Figure 1 is a side elevation of the gas cock disclosing the position of the operating lever, when the valve is closed, in full lines, the dotted lines indicating the position of 30 the said operating lever when the same is held by the expansion of a rod adjacent to the flame. Fig. 2 is an end elevation of Fig. 1 disclosing the manner in which the expansion rod is held adjacent to the flame 35 and is operatively connected to the retaining lever which in turn holds the operating lever in a position which will hold the gas valve open. Fig. 3 is a broken vertical sectional view of the gas cock with the valve closed, 40 and Fig. 4 is a similar view disclosing the valve in an open position.

I have provided means for automatically shutting off the supply of gas when the flame is extinguished by means of the device which 45 may be described as follows:

Referring to the drawings, the numeral 1 is used to designate a horizontal tubular member having an ordinary gas cock 2 therein and a vertically disposed tubular extension 3, to the upper end of which is secured a gas tip 4. The lower end of the bore 5 of the extension 3 is provided with a valve seat 6. A valve 7 is normally seated on the seat 6 by means of a suitable spring 8, the tension

of which may be regulated by the plug 9 55 screwed into the opening 10 of the horizontal tubular member 1.

Pivotedly mounted within the member 1 is a counter shaft 12 to which is secured an inner lever 14, the outer end of which engages an aperture 15 in the valve 7. The outer end of the counter shaft 12 is secured to an outer lever 16, having an eyelet 17 in the end thereof so that a chain or suitable cord, not shown, may be attached thereto. 60 The outer lever 16 lies between a rib 18 secured to the vertical extension 3 and a retaining lever 19, pivotally secured as at 21 to the upper end of the said extension 3, and having an inner surface 20 parallel with 70 the vertical rib 18 secured to the said extension 3. The upper end of the retaining lever 19 engages the end of the expansion rod 22, the threaded portion 23 of which is secured in the upper end of an arm 26 integral with 75 the upper end of extension 3. The expansion rod 22 is provided at its outer end with a suitable thumb nut 27 by means of which the said expansion rod 22 may be turned so as to adjust the distance between the upper 80 ends of the arm 26 and the retaining lever 19.

The operation is as follows: The gas cock 2 is opened and the outer lever 16 pulled downward to the position indicated by dotted lines in Fig. 1 of the drawings, which 85 will cause the inner lever 14 to unseat the valve 7 and hold the same unseated against the tension of the spring 8 by means of the lever 14 as indicated in Fig. 4 of the drawings. The gas will then flow through the 90 tip 4 and is ignited in the usual manner. The heat from the burning gas will cause the rod 22 to expand and force the upper end of the retaining lever 19 outward which will cause the lower end of the said retaining 95 lever 19 to move inward and firmly grip the lever 16 and hold the same in the position indicated in the dotted lines of Fig. 1 of the drawings which will retain the valve 7 in an open position as disclosed in Fig. 4 of the 100 drawings. If, in any manner, the flame, which I have indicated by means of dotted lines in Figs. 1 and 2 of the drawings, should be extinguished, the expansion rod 22 will rapidly cool and contract, the said contraction decreasing the distance between the arm 26 and lever 19 thereby releasing the said retaining lever 19 and the outer lever 16

which will in turn release the valve 7 when the spring 8 will return the said valve 7 to the seat 6 of the bore 5 within the extension 3 and prevent a further flow of gas.

5 The distance between the surface 20 of the lever 19 and the rib 18 on the extension 3 may be regulated so as to properly engage the outer lever 16 when the rod 22 is expanded by turning the thumb nut 27 which 10 will increase or decrease the distance between the upper ends of the lever 19 and the arm 26, according to the direction in which the said thumb nut is turned. The expansion rod 22 is threaded as at 23 for the further 15 purpose of taking up any movement occasioned by wear on the several parts.

It is obvious from the foregoing that I have provided improved means whereby the 20 flow of gas through a jet or the like will be automatically shut off when the flame is extinguished.

The details of construction being so susceptible to variation, I do not wish to confine myself to the precise construction shown 25 herein but rather to avail myself of any modification that may properly fall within the scope of my invention.

Having thus disclosed my invention what I claim as new and desire to secure by Letters Patent is—

1. An automatic gas cock comprising a horizontal tubular member having a vertical extension thereto; a valve seat between the horizontal and the vertical members; a valve adapted to normally engage the valve seat; a lever rotatably mounted within the horizontal member and adapted to engage the valve and remove the same from the valve seat; a second lever secured to the lever within the horizontal member; a rib secured to the outer surface of the vertical extension; a retaining lever pivotally secured to the vertical extension and having a surface parallel with the rib on the extension; and adapted to engage the second lever between the said parallel surface and the said rib and an expansion rod secured above the gas jet and adapted to operate the retaining lever and rigidly secure the second mentioned lever when the said rod is expanded and to release the said lever when the rod is contracted.

2. In an automatic gas cock, the combination of a horizontal tubular member having a vertical extension with an arm integral therewith; a valve seat between the horizontal and vertical members; a valve adapted to engage the valve seat; means for normally retaining the valve on the seat; a counter shaft rotatably mounted within the horizontal member; an inner lever secured to the said shaft and adapted to engage the valve and retain the same from its seat; an outer valve secured to the said shaft; a rib 60 secured to the outer surface of the vertical 65 extension; a retaining lever pivotally secured to the vertical extension and parallel with the rib thereon, said lever being adapted to engage the outer lever between the said retaining lever and the rib on the vertical extension; and an expansion rod secured to the arm on the extension and adapted to engage the upper end of the retaining lever

extension; a retaining lever pivotally secured to the vertical extension and parallel with the rib thereon, said lever being adapted to engage the outer lever between the said retaining lever and the rib on the vertical extension; and an expansion rod secured to the arm on the extension and adapted to engage the upper end of the retaining lever and cause the lower end of the said lever to securely engage the outer lever between the said retaining lever and the rib and hold the valve from its seat when the said rod is expanded and to release the retaining lever and the outer lever when the said rod is contracted.

3. In an automatic gas cock, the combination of a horizontal tubular member having a vertical extension with an arm integral therewith; a valve seat between the horizontal and vertical members; a valve adapted to engage the valve seat; means for normally retaining the valve on the seat; a counter shaft rotatably mounted within the horizontal member; an inner lever secured to the said shaft and adapted to engage the valve and retain the same from its seat; an outer valve secured to the said shaft; a rib secured to the outer surface of the vertical extension; a retaining lever pivotally secured to the vertical extension and parallel with the rib thereon, said lever being adapted to engage the outer lever between the said retaining lever and the rib on the vertical extension; and an expansion rod secured to the arm on the extension and adapted to engage the upper end of the retaining lever and cause the lower end of the said lever to securely engage the outer lever between the said retaining lever and the rib and hold the valve from its seat when the said rod is expanded and to release the retaining lever and the outer lever when the said rod is contracted; and means for regulating the pressure of the valve on its seat.

4. In an automatic gas cock, the combination of a horizontal tubular member having a vertical extension with an arm integral therewith; a valve seat between the horizontal and vertical members; a valve adapted to engage the valve seat; means for normally retaining the valve on the seat; a counter shaft rotatably mounted within the horizontal member; an inner lever secured to the said shaft and adapted to engage the valve and retain the same from its seat; an outer valve secured to the said shaft; a rib secured to the outer surface of the vertical extension; a retaining lever pivotally secured to the vertical extension and parallel with the rib thereon, said lever being adapted to engage the outer lever between the said retaining lever and the rib on the vertical extension; and an expansion rod secured to the arm on the extension and adapted to engage the upper end of the retaining lever

and cause the lower end of the said lever to securely engage the outer lever between the said retaining lever and the rib and hold the valve from its seat when the said rod is expanded and to release the retaining lever and the outer lever when the said rod is contracted; means for regulating the pressure of the valve on its seat; and means for regulating the length of the expansion 10 rod between the arm on the vertical exten-

sion and the upper end of the retaining lever.

In witness whereof I hereunto set my signature in the presence of two subscribing witnesses.

ALTON R. WEAVER.
